Samuel Stearns
ATTORNEY

UNITED STATES PATENT OFFICE

JOHN HOMER PLUNKETT, OF BEVERLY HILLS, CALIFORNIA, ASSIGNOR TO THE FLINTKOTE COMPANY, OF BOSTON, MASSACHUSETTS, A CORPORATION OF MASSACHUSETTS

WATERPROOF CONSTRUCTION MATERIAL

Application filed August 12, 1929. Serial No. 385,098.

This invention relates to a building material especially suitable for thermally insulating and waterproofing walls, ceilings, or the like.

- 5 It is an object of my invention to provide a construction material of the character described which is inexpensive to manufacture and which can be rapidly and economically applied in use.
- 10 Another object of my invention is to provide a construction material which is capable of rapid application to walls, ceilings, etc. to form a barrier thereon against the entrance or penetration of water or moisture, and which is susceptible of use as well upon exterior as upon interior walls.

Still another object of the invention is to provide a construction material of the type described, wherein a backing material waterproofed on its opposite surfaces is formed on one of such surfaces with a reenforcing sheet or membrane of fibrous material, which is itself quite tough and durable so as to act effectively as a reinforcement for the backing, and at the same time sufficiently porous or absorbent to be readily wetted by water so that when the surfacing material such as plaster or stucco is applied thereover, the latter will be permanently bonded to the 20 backing by the suction incident to the abstraction of water by the porous membrane from the plastic stucco or plaster.

Still a further object of the invention resides in the provision of a construction material of the type described having indicia suitably printed thereon to guide the workman in properly and rapidly applying the material to a foundation, such as a wall, ceiling or the like.

40 Still other objects of the invention as well as numerous advantages thereof will appear from the following more detailed description and from the accompanying drawings, in which,

45 Figure 1 is a view showing the manner in which my novel construction material is employed in successive overlapping courses in a wall or similar structure.

50 Figure 2 is a view in perspective showing

the arrangement of the material in the successive courses.

Figure 3 is a vertical section through a completed wall in which my novel material is utilized, and

55 Figure 4 is a somewhat magnified view illustrating the material per se.

According to my invention, sheets of 60 felted fibrous material, such for example as roofing felt made from rag fibres or the like in a well known manner to produce a bibulous sheet, is first saturated thoroughly with a waterproofing substance as for example asphalt of about 130 to 150° F. melting point. This saturation may be readily accomplished by immersing the sheet for a substantial period of time in a bath of the molten asphalt maintained at a temperature such that the asphalt is sufficiently 65 fluid to enter the pores and interstices of the felted fibrous sheet and thereby completely impregnate the latter. To this end the temperature of the bath will generally be maintained at approximately 400 to 420° F. After the sheet has been saturated, it 70 is then coated on both faces thereof as by means of coating rolls or sprays with a waterproofing material similar in its nature to that employed for impregnating the sheet but of somewhat higher melting point, as for example 200 to 220° F. This coating material is maintained at such a temperature that it will remain on the surfaces of the sheet in relatively thin layers, and for this purpose the coating material, when 75 employing asphalt of 200 to 220° F., will generally be maintained and supplied to the surfaces of the sheet at about 380-410° F.

80 The thus impregnated and coated sheet provides a foundation or backing which for all practical purposes within the purview of my invention is entirely waterproof as well as damp-proof. For achieving the principal objects of my invention, however, I affix to one surface of the impregnated and coated backing reinforcing membrane of tough durable paper, having a relatively 85 smooth surface finish, but which is sufficiently porous and water absorptive to act as

an effective key for bonding plaster, stucco or the like to the backing. It is essential also that this surface membrane should not be subject to ready disintegration as by abrasion, for in that event, the asphaltic coating material on the surface of the backing which carries this membrane will become exposed and prevent plaster, stucco, etc. from effectively bonding therewith. I find that a relatively thin sheet of kraft paper, 10 fulfills the aforesigned requirements, at a minimum of cost. While kraft paper is sufficiently water absorptive for the purposes above named, its nature is such that it can be readily applied to the coated face 15 of the backing without any of the asphaltic coating material striking through the kraft. At the same time it is sufficiently tough to reinforce the impregnated and coated base. It will be understood, however, that any sheet made from vegetable fibers and similar to kraft paper in respect to the aforesigned properties, may be used.

The kraft paper which is preferably thinner than the backing of saturated and coated felt, may be combined with a surface of the impregnated and coated backing sheet of felt at a convenient time after the coating material has been applied to the sheet and before it has entirely cooled and set, so that the sticky nature of the asphalt coating may act as an adhesive for the sheet of kraft. The face of the backing sheet opposite that to which the kraft is affixed, may, if desired, be dusted with powdered mica, talc or the like to relieve this face of the normal tackiness characteristic of the asphaltic coating material.

40 The sheet as thus prepared may be made in any desired lengths and of suitable widths, and wound into rolls for shipment.

In Figure 4, I have depicted the structure of this material prepared as above set forth. Numeral 10 indicates the sheet as a whole, numeral 11 indicates the base or foundation of felt, such as ordinary roofing felt, saturated with asphalt or similar waterproofing substance, and numerals 12, 12a indicate the layers of asphalt coating material upon the opposite faces of the foundation sheet 11. The sheet of kraft paper affixed to one of the coated faces of the foundation is indicated at 13 while fine mineral, such as powdered talc or mica upon the opposite coated face thereof is indicated at 14.

The material as thus constructed has been particularly devised and formed especially suitable for thermally insulating waterproofing walls, ceilings or the like. For this purpose, the sheets are preferably applied in courses to studding or the like with the face of the sheet carrying the kraft paper outermost, and with a margin of each sheet

partially overlapping the sheets of the preceding course. In Figures 1 and 2, I have shown the sheets 10 applied to studding 15 in horizontally overlapping courses.

In order to guide the workman in rapidly applying the material to a foundation, such as studding or the like, in overlapping courses, with the sheets of each course in proper alignment and without more than the requisite overlap between successive courses, 70 a line or band 16 may be printed or otherwise formed on the outermost face of the sheet of kraft 13, near one margin thereof. When the band 16 is made relatively wide, the workman may be directed to lay the successive courses either to the upper or lower boundaries of the band, according to the requirements of the user, but in either case by positioning the band at an appropriate distance from one margin of the sheet, the 80 overlap necessary to provide adequate protection against leaks, etc. will be afforded. 85

An important feature of the material constructed in accordance with my invention resides in its perfect bonding qualities with plaster, stucco, or the like, due to the water-absorptive properties of the kraft paper embodied therein, and the consequent production of a keying suction which enables the plastic or stucco permanently to adhere to 90 the surface thereof. Figure 3 illustrates several courses of my improved insulating and water-proofing material applied to an interior wall and surmounted by a layer of plaster 17, the plaster being applied over 100 the kraft covered face of the backing 10, which as already stated faces outermost, and serves as a bonding medium for the plaster.

For exterior work, such as exterior stucco 105 and cement, the material of my invention serves admirably as an insulating and water-proofing membrane behind the wire both ordinarily employed in exterior work.

Furthermore, this material is suitable for 110 use as a water-proofing and insulating liner for brick, veneer, or wood frame constructions, and hence will find wide application in the building industry as a water-proofing and thermal insulation medium. 115

I claim as my invention:

1. A building material suitable as a backing for plaster, stucco and the like, comprising lengths of felted fibrous material saturated with a water-proofing substance and coated on its surfaces with a layer of bituminous material, one of said coated surfaces having affixed thereto throughout its entire extent, a sheet of water-absorptive, smooth, and relatively tough paper. 120

2. A building material suitable as a backing for plaster, stucco and the like, comprising lengths of felted fibrous material saturated with a water-proofing substance and coated on its surfaces with a layer of bitu- 125

minous material, one of said coated surfaces having affixed thereto throughout its entire extent, a sheet of kraft paper.

3. A building material of the character described, comprising a felted fibrous foundation saturated with a water-proofing substance and coated on its surfaces with a layer of bituminous material, one of said coated faces having affixed thereto throughout its entire extent, a sheet of water-absorptive, smooth and relatively tough paper, said sheet of paper being relatively thinner than said foundation.

4. A building material of the character described, comprising a felted fibrous foundation saturated with a water-proofing substance and coated on its surfaces with a layer of bituminous material, one of said coated faces having affixed thereto throughout its entire extent, a sheet of kraft paper, said sheet of paper being relatively thinner than said foundation.

5. A building material suitable as a backing for plaster, stucco and the like, comprising lengths of felted fibrous material saturated with a water-proofing substance and coated on its surfaces with a layer of bituminous material, one of said coated surfaces having affixed thereto throughout its entire extent, a sheet of water-absorptive, smooth, and relatively tough paper, said sheet of paper having a narrow guide band imprinted thereon adjacent one of its longitudinal edges.

35 6. A building material suitable as a backing for plaster, stucco and the like, comprising lengths of felted fibrous material saturated with a water-proofing substance and coated on its surfaces with a layer of bituminous material, one of said coated surfaces having affixed thereto throughout its entire extent, a sheet of kraft paper, said sheet of kraft having a narrow guide band imprinted thereon.

45 7. In combination with structure of plaster, stucco, or the like, an underlining therefore, comprising partially overlapped sheets of fibrous felt, each of said sheets being impregnated with a water-proofing substance and coated on its surfaces with a layer of bituminous material, the coated surface adjacent the plaster, having affixed thereto throughout its entire extent, a sheet of water-absorptive, smooth, and relatively tough paper.

55 8. In combination with a structure of plaster, stucco, or the like, an underlining therefore, comprising partially overlapped sheets of fibrous felt, each of said sheets being impregnated with a water-proofing substance and coated on its surfaces with a layer of bituminous material, the coated surface adjacent the plaster, having affixed thereto throughout its entire extent, a sheet of kraft paper.

9. In combination with structure of plaster, stucco, or the like, an underlining therefore, comprising partially overlapped sheets of fibrous felt, each of said sheets being impregnated with a water-proofing substance and coated on its surfaces with a layer of bituminous material, the coated surface adjacent the plaster, having affixed thereto throughout its entire extent, a sheet of kraft paper having a guide line imprinted thereon parallel to and spaced from one of the longitudinal edges thereof, the successive overlapping sheets having the lower edges thereof positioned along one of the boundaries of said guide line on the subjacent sheet.

Signed at Los Angeles, in the county of Los Angeles, and State of California, this second day of August, A. D. 1929.

DISCLAIMER

1,813,081.—*John Homer Plunkett*, Beverly Hills, Calif. WATERPROOF CONSTRUCTION MATERIAL. Patent dated July 7, 1931. Disclaimer filed May 9, 1935, by the assignee, *The Patent and Licensing Corporation*.

Hereby enters this disclaimer to that part of the specification of the aforesaid Letters Patent which consists of claims 1, 2, 3, 4, 7 and 8 which are in the following words, to wit:

“1. A building material suitable as a backing for plaster, stucco and the like, comprising lengths of felted fibrous material saturated with a water-proofing substance and coated on its surfaces with a layer of bituminous material, one of said coated surfaces having affixed thereto throughout its entire extent, a sheet of water-absorptive, smooth, and relatively tough paper.

“2. A building material suitable as a backing for plaster, stucco and the like, comprising lengths of felted fibrous material saturated with a water-proofing substance and coated on its surfaces with a layer of bituminous material, one of said coated surfaces having affixed thereto throughout its entire extent, a sheet of kraft paper.

“3. A building material of the character described, comprising a felted fibrous foundation saturated with a water-proofing substance and coated on its surfaces with a layer of bituminous material, one of said coated faces having affixed thereto throughout its entire extent, a sheet of water-absorptive, smooth and relatively tough paper, said sheet of paper being relatively thinner than said foundation.

“4. A building material of the character described, comprising a felted fibrous foundation saturated with a water-proofing substance and coated on its surfaces with a layer of bituminous material, one of said coated faces having affixed thereto throughout its entire extent, a sheet of kraft paper, said sheet of paper being relatively thinner than said foundation.”

“7. In combination with structure of plaster, stucco, or the like, an underlining therefore, comprising partially overlapped sheets of fibrous felt, each of said sheets being impregnated with a water-proofing substance and coated on its surfaces with a layer of bituminous material, the coated surface adjacent the plaster, having affixed thereto throughout its entire extent, a sheet of water-absorptive, smooth, and relatively tough paper.

“8. In combination with a structure of plaster, stucco, or the like, an underlining therefore, comprising partially overlapped sheets of fibrous felt, each of said sheets being impregnated with a water-proofing substance and coated on its surfaces with a layer of bituminous material, the coated surface adjacent the plaster, having affixed thereto throughout its entire extent, a sheet of kraft paper.”
